UNITED STATES PATENT OFFICE.

HANS WILHELM ROBERT THORELLI, OF NORRVIKEN, SWEDEN, ASSIGNOR TO TELE-
FONAKTIEBOLAGET L. M. ERICSSON, OF STOCKHOLM, SWEDEN, A COMPANY OF
SWEDEN.

MACHINE-DRIVEN SELECTOR.

Application filed May 23, 1928, Serial No. 280,040, and in Sweden May 30, 1927.

The invention relates to such machine driven selectors for automatic telephone systems which are set under the control of impulse registers or similar numerical switching apparatus and which are provided for said purpose with an impulse sender actuated by the driving or motion mechanism of the selector to send control impulses to the register, and, in addition, 55
5 switching apparatus and which are provided for said purpose with an impulse sender actuated by the driving or motion mechanism of the selector to send control impulses to the register, and, in addition, 55
10 an electromagnetic locking device controlled from the register for locking the movable switch arm of the selector in each position. The maximum speed of such selectors is in a marked degree dependent upon 60
15 the speed at which said locking device can be brought into operation due to the fact that the switching process by which the locking device is caused to operate comprises a series of operations of different 65
20 switching devices such as relays and clutch magnets which require a certain amount of time for their operation. To be able to drive the selectors at a high speed in spite of the above mentioned difficulties, it has 70
25 previously been proposed to displace the impulse sender of the selector and the locking device in relation to each other in such a manner that said switching process is 75
started already before the movable switch 80
30 arm of the selector has attained the desired setting position. From practical reasons 85
said displacement between the impulse sender and the locking device must not, however, be too large. It is necessary to take into account that the time required for 90
35 said switching process is somewhat different for different switching devices and, further, that the speed of the selector may vary due to variations in the voltage of the 95
40 current supply for the driving mechanism of the selector. Considering the above mentioned variations in the speed of operation of the switching devices and the speed of the selector rather narrow limits of adjustment are obtained which to a certain degree put a limit to any increase in the setting speed of the selector. The object of 100
45 the present invention is to eliminate said inconvenience. The invention principally 105
50 consists therein that the switching process by which the locking device is brought into operation is started by that impulse by which the register is set into the marked position, but is not completed until a suc-

ceeding impulse is sent from the impulse 55 sender of the selector before the selector has reached the desired setting position. It is thus possible to operate with a complete reliability having the impulse sender and the locking device displaced a distance corresponding to as far as double the distance between adjacent setting positions of the selector.

The invention will be more closely described with reference to the accompanying 65 drawing which illustrates a circuit diagram in which only those parts of the selector and the register which concern the present invention are shown.

The impulse sender of the selector comprises a bar IS connected to the movable switch arm and provided with teeth IT adapted to cooperate with a contact spring IK which is included in the impulse circuit leading to the register. A locking bar 70 SS is further permanently connected to the movable switch arm of the selector. Said switch arm can be locked by means of said locking bar in any setting position through a detent SH adapted to be actuated from 75 the register by means of an electro-magnet SM.

The impulse register includes a number of primary register switches RS₁, RS₂ which in known manner receive impulses from the 85 impulse sender of the subscriber or of the operator respectively, a contact arm not shown being then set to connect a contact in the corresponding contact banks RK₁ and RK₂ to a contact bar KS₁ and KS₂ respectively. The register also comprises a number of secondary register switches IM₁, IM₂ which receive the impulses sent from the 90 selectors through the medium of an impulse relay IR, and which are provided with contact banks IK₁ and IK₂ respectively which are connected to the contact banks of the primary register switches in a certain manner in order to obtain a translation to that 95 numerical system according to which the contacts of the contact fields of the selectors are grouped. In the example shown it is assumed that the selector has 25 setting positions. In accordance herewith the secondary register switch IM₁ is provided with 25 100 contacts which are connected to the contacts in the primary register switch RS₂ as indicated on the drawing and combined with 105

three contact bars KS_2 , KS_3 , KS_4 which are connected to the first three contacts in the switch RS_1 . In the present case the secondary register switches are assumed to be of that kind which are moved forward two steps for each impulse from the selector i. e. one step at the closing and one step further at the interruption of the current. The number of impulses required for the setting of the selector is thus reduced to the half and, consequently, the number of teeth IT on the impulse bar IS is only half the number else required. The vertical lines 1, 2, 3 etc, which are drawn between the different locking teeth on the bar SS indicate the locking positions corresponding to the setting positions of the selector. These lines also indicate that the impulse bar IS and the locking bar SS are so displaced in relation to each other that the detent SH has not yet reached the first locking position in the movement when the impulse current is closed through the contact spring IK upon a displacement of the bars in the direction of the arrows. Said locking position is not reached until the free end of the contact spring has left the first tooth IT . The result aimed at by said displacement of the impulse bar IS in relation to the locking bar SS may, of course, also be obtained by displacing the contact spring IK and the detent SH in a corresponding manner relatively each other.

The selector is adapted to be driven by machine power from a continuously rotating shaft to which the selector is coupled by means of an electro-magnetic clutch KM . The different switching operations are controlled in a manner usual in machine driven systems i. e. by means of a control switch or a sequence switch of which only the contacts SO_1 , SO_2 , SO_3 required for the present purpose are shown.

The switching operation proceeds in the following manner. After the register switches RS_1 , RS_2 have been set, the sequence switch is actuated and the contacts SO_1 , SO_2 , SO_3 are thus closed. A circuit 11 is then closed through the locking magnet SM which actuates the detent SH and releases the switch arm of the selector and also the bars IS and SS secured to the switch arm. At the same time the detent SH closes at the contact K_1 , a circuit 12 through the clutch magnet KM thus starting the selector. Simultaneously with the starting of the selector the magnet of the register switch IM_1 is energized by a current impulse over a circuit 13, the register switch being thus advanced one step. During the movement of the selector the teeth on the impulse bar IS will actuate the contact spring IK , an impulse circuit 14 being thus closed and opened alternately. When said circuit is closed the impulse relay IR is actuated which then opens

the circuit 13 for the register switch IM_1 which is thus moved forward for another step. When the contact spring IK has passed the first tooth the impulse circuit is interrupted, the register switch IM_1 being then moved forward another step. In this manner the operation proceeds, the register switch being advanced one step for each closing and another step for each interruption of the impulse circuit, until said switch reaches the contact bar marked by the register switch RS_1 and the contact marked by the switch RS_2 . If the impulse relay IR is then current carrying a circuit 15 is closed which includes a relay SR_1 which is energized and connects itself into a holding circuit 16, the interruption of the circuit 11 of the locking magnet SH being thus prepared. The last mentioned circuit remains, however, still closed by another relay SR_2 which is not actuated until the selector has passed the next impulse position in which the impulse relay IR is de-energized and closes a circuit 17 for the relay SR_2 which in turn interrupts the circuit 11 for the locking magnet SM . At the same time the register switch IM_1 is moved forward one step, the circuit 17 being then opened. Already before then, however, the relay SR_2 has obtained holding current over a circuit 18. The circuit 11 of the locking magnet SM is therefore now definitely interrupted. The last interruption in the impulse circuit 14 occurred when the detent SH passed or had just passed that setting position which precedes the position in which the selector is required to stop. When the detent SH is released it will thus lock the selector in the correct position. Upon being released it will in the first moment bear against the upper surface of the tooth on the left hand side of the locking position, the circuit 12 thus remaining closed and the selector continuing its movement till it has been centered in the position in question.

As will be understood from the foregoing description, the displacement between the impulse sender and the locking device is so adjusted that the selector after the sending of that impulse which brings the register in an operative position will have to pass a distance corresponding to about double the distance between two adjacent contact positions, before it is locked in the desired position. Such large displacement has been made possible by dividing the switching process which brings the locking device into operation into the two phases which are controlled by two consecutive impulses from the selector, the locking being prepared by the first impulse and completed by the second.

I claim:

An arrangement in machine driven selectors of the kind which are set under the control of a register or other similar numerical

switching apparatus and which for this purpose are provided with an impulse sender actuated by the mechanism of the selector for sending control impulses to the register, 5 and an electro-magnetic locking device actuated from the register for locking the movable switch arm of the selector in the set position, characterized by the impulse sender and the locking device being displaced in 10 relation to each other in such a manner that

the switching process which brings the locking device into operation is started by that impulse whereby the register is set into operative position and is completed by a succeeding impulse which is sent from the impulse 15 sender, before the selector has reached the desired setting position.

In testimony whereof I affix my signature.

HANS WILHELM ROBERT THORELLI.
